UNITED STATES PATENT OFFICE.

HERBERT H. WYDOM, OF BOSTON, MASSACHUSETTS, ASSIGNOR TO HOOD RUBBER COMPANY, OF WATERTOWN, MASSACHUSETTS, A CORPORATION OF MASSACHUSETTS.

DESIGN FOR A COMBINED SOLE AND HEEL.

Application filed December 13, 1927. Serial No. 24,473. Term of patent 14 years.

To all whom it may concern:

Be it known that I, HERBERT H. WYDOM, a citizen of the United States, residing at Boston, in the county of Suffolk and State of Massachusetts, have invented a new, original, and ornamental Design for a Combined Sole and Heel, of which the following is a specification, reference being had to the accompanying drawing, forming part thereof.

Referring to the drawing:

Fig. 2 is a sectional elevation taken on line 2—2 of Fig. 1.

Fig. 3 is a sectional elevation taken on line 3—3 and broken away.

I claim:

The ornamental design for combined sole and heel, as shown.

HERBERT H. WYDOM.
